Primary Examiner—Alan P. Douglas*Assistant Examiner*—Caron D. Veynar*Attorney, Agent, or Firm*—Owen, Wickersham & Erickson[57] **CLAIM**

The ornamental design for a cast broiling pan, as shown and described.

DESCRIPTION

FIG. 1 is a perspective view of the invention;
FIG. 2 is an exploded perspective view of the invention;
FIG. 3 is a front elevation view of the grill shown separately for ease of illustration, the rear elevation view being a mirror image;
FIG. 4 is an end view of one end of a grill of the invention, the other end being a mirror image;
FIG. 5 is a top view of a grill of the invention;
FIG. 6 is a bottom view of a grill of the invention;
FIG. 7 is a front elevation view of the pan shown separately for ease of illustration, the rear elevation view being a mirror image;
FIG. 8 is an end view of a pan of the invention, the other end being a mirror image;
FIG. 9 is a top view of a pan of the invention;
FIG. 10 is a bottom view of a pan of the invention;
FIG. 11 is a cross-sectional view of the invention as shown in FIG. 1 taken at 11—11; and,
FIG. 12 is a side cross-sectional view of the invention of FIG. 1 taken at 12—12.
